UNITED STATES PATENT OFFICE.

WILLIAM ALBERT SHELDON, OF CHICAGO, ILLINOIS.

APPARATUS FOR PRESERVING.

SPECIFICATION forming part of Letters Patent No. 657,276, dated September 4, 1900.

Application filed May 4, 1899. Serial No. 715,608. (No model.)

To all whom it may concern:

Be it known that I, WILLIAM ALBERT SHELDON, a citizen of the United States, residing at Chicago, in the county of Cook and State of Illinois, have invented certain new and useful Improvements in Apparatus for Preserving, &c., and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to an apparatus for continuously and automatically changing the position of eggs, fruit, and other articles and commodities which if permitted to remain undisturbed or in one position for an appreciably-long time will deteriorate in value, appearance, and quality. To accomplish this result, the eggs, fruit, &c., are packed, so as not to become disarranged, in suitably-formed cases, which may be cylindrical, rectangular, or other convenient shape and so supported that they will be slowly but continuously rolled or rotated around their axes about once in twenty-four hours. The rolling motion, which continues during the time the articles are in storage or transit, is an alternating one—that is to say, turning first in one direction for a certain number of revolutions and then in the opposite direction for an equal number of turns. By this treatment the component parts of the aforesaid articles which tend to separate according to their various specific gravities or to pack from their weight, as with fruits when retained in one position for a lengthened period, and thus deteriorate and spoil, retain their natural conditions for a much longer time, so that when brought to market they are fresher, more wholesome, and present a more perfect and attractive appearance than similar articles not so treated. The cases within which the articles to be treated are placed may be of any shape, as heretofore stated, and may roll directly on the floor or on the floors or platforms fastened to the framing at various elevations, or the cases may have a trunnion projecting from each end to rest and roll on a rail on each side of the apparatus.

When the articles are heavy, it may be best to place the cases on the floor.

In the accompanying drawings, Figure 1 is a side elevation of my apparatus. Fig. 2 is a horizontal section therethrough on the line 2 2. Fig. 3 is a vertical cross-section on the line 3 3 of Figs. 1 and 2. Fig. 4 is an enlarged view of the speed-regulating mechanism. Figs. 5 and 6 are views showing two modified means for operating the packing-cases. Fig. 7 illustrates a further modification.

1 and 2 indicate two frames, each of which consists of upright bars A and horizontal bars C, bolted to said upright bars. The horizontal bars C of each frame, which lie parallel to and are separated from one another, extend from the top to the bottom of the upright bars A and form supports or rails for cases or receptacles, as hereinafter described. The frames 1 2, which are placed parallel to each other, extend lengthwise any desirable distance and may rise vertically from floor to ceiling. Brackets a are conveniently used to fasten the frames to floor and ceiling or to overhead beams B. The distance between the frames 1 2 is regulated by the length of the cases or receptacles D, which are placed therein. The horizontal bars C of each frame 1 2 are equal in number and so arranged that the upper surfaces of corresponding bars lie in the same plane, and thus form rails on which the cases revolve.

Between the frames 1 and 2 and supported on the several horizontal bars or rails C are a number of packing or holding cases or receptacles D, which may be of cylindrical, square, rectangular, or other form, each end of each case or receptacle being provided with a projecting pin or trunnion d, which is adapted to rest on one of the rails C in each frame. The trunnions d may rest directly on the bars C or on strap-iron secured thereto; but the preferred form is that shown in the drawings, which consists of a piece of angle-iron E, bolted to the upper edge of each bar C in such position that one side of each angle-iron lies in an upright position, on the edge of which a trunnion d rests. The cases thus supported are rolled very slowly on their trunnions backwardly and forwardly, constantly changing the position of articles with-

in the cases and preventing the separation by gravity of their constituent parts or the packing, as with fruits, which would be the result were they to remain in one position for a relatively-long time. Instead of supporting the cases by trunnions resting on rails they may rest on the floor (see Fig. 7) or on platforms built across the apparatus from one frame to another and secured to the horizontal bars or rails C.

To provide means for rolling the cases and at the same time to prevent them from coming into contact with one another while being rolled, a notched draw-bar F is placed on each side of the apparatus between each angle-iron E and the adjacent ends of the cases D the notches f in the draw-bar engaging with the trunnions d. The draw-bars F are in this instance made of strap metal and stand edge-wise, the notches f extending from their lower edges upwardly about half the width of the bar. When the draw-bars F are in place, the trunnions d are engaged by the notches f, which are so spaced that the cases are kept separated and free from all danger of contact. The draw-bars F extend from one end of the frame to the other, each pair which rotate the same cases being connected at the operating end of the apparatus by a cross-bar f', from which point the draw-bars are bent toward each other and joined, the united ends f² extending again in a straight line, a rack F' being secured to the said united ends.

A vertical shaft G at one end of the apparatus, and driven by means hereinafter described rests at its lower end in a step g, from which it can be readily removed when found necessary or desirable to remove the cases from this end of the apparatus. Fixed to the shaft G are a series of pinions H, each pinion being adapted to engage with one of the racks F' on the united ends of a pair of draw-bars F. The shaft G, which is caused to rotate first in one direction and then in the other, causes the draw-bars through their connections to reciprocate, the length of movement depending upon the diameters of the pinions H. By using pinions of different diameters different lengths of travel and different speeds may be imparted in one apparatus to the several draw-bars and through them to the cases. The number of rotations of the cases in a given length of movement of the draw-bars F may be increased or diminished by the use of trunnions of different diameters. If trunnions of one-half ($\frac{1}{2}$) inch diameter are used, one rotation of the case will advance it in a linear direction one and four-sevenths ($1\frac{4}{7}$) inches or eleven (11) inches in seven (7) revolutions of the case, and thus if only one revolution is made in twenty-four (24) hours a space of only eleven (11) inches will be needed to continue the rolling in one direction for a week. The shaft G is given 65 rotation by means now to be described.

Adapted to turn in bearings fixed to the frame 2 or to the ceiling or beams B is a shaft

I, horizontally disposed near the top of the apparatus. Keyed or otherwise fixed to the shaft I are two bevel gears J K, so arranged as to mesh with and on opposite sides of a bevel-gear L on the upper end of the vertical shaft G. The three bevel-gears have the same pitch-diameter; but while the bevel-gear L has its full complement of teeth the bevel-gears J and K are without teeth for about one-half their diameters, or thereabout, and so adjusted on the shaft I that the toothed half of one gear is opposite the mutilated half of the other. By this arrangement the continuous rotation of the shaft I in one direction will cause the mutilated gear, which is in engagement with the gear L, to turn the shaft G in one direction until the last tooth of said mutilated gear is on the point of becoming disengaged from the gear L, at which moment the first tooth of the other mutilated gear will enter into engagement with the said gear L and rotate it in the opposite direction, at the end of which movement the first-mentioned mutilated gear will again come into engagement with the gear L.

On the horizontal shaft I is fixed a drum M, around which a rope or chain N is wound. One end of said rope carries a weight O, which may be increased or diminished as required, while the other end passes down from the drum M to and around a windlass P and attached thereto. The windlass P turns on a shaft Q, journaled in bearings fixed to a frame 3. The outer end of the windlass P has a hand-crank p by which it is rotated. The inner end of the shaft Q carries two mutilated bevel-gears R S, similar to the gears J K, which engage alternately with a bevel-gear T, fixed on a shaft U, journaled at a right angle to shaft Q and horizontally to it. It is obvious that proper gears may be introduced between the shaft Q and the pendulum to reduce the speed of the pendulum to about one beat per second, more or less, and that the mutilated gears may be connected with the pendulum-shaft, and to swing the pendulum any approved clockwork mechanism may be employed. A supporting-plate V on the outer end of the shaft U has pivoted thereto a pendulum W, its bob w being adjustable on the bar w' and secured thereto when adjusted by means of a screw x. A pin v projects from the plate V on each side of the pendulum-bar.

The driving mechanism described possesses many advantages where an exceedingly-slow speed is desired. The weight is wound up by turning the crank p, which, winding the rope N about the windlass, draws it from the drum, and the latter being thereby rotated raises the weight. Suitable ratchet mechanisms are interposed between the windlass and the drum and their respective shafts to permit this winding action. The tendency of the weight being to descend, the shaft I is caused to turn and through the bevel-gears J, K, and L operate the shaft G and the cases.

The rotation of the drum also draws the rope from the windlass P, turning it, the shaft Q, and, through the intermediate gears, the mutilated bevel-gears R S on said shaft. The mutilated gears R S cause the bevel-gear T and its shaft U to rock, thus swinging the pendulum W first to right and then to left. The speed of the mechanism is regulated by the pendulum W, the length of which may be changed, as also the weight of the bob w. The longer and heavier the pendulum the slower the speed. The proportions between the diameters of the drum and the windlass may also vary. It is always desirable, however, to have a drum of greater diameter than the windlass. Change of proportion between the gears will also cause a change of speed.

The means shown in Figs. 1, 2, and 3 for rolling the cases and keeping them separated a predetermined distance at all times, while being a simple and therefore the preferred form, I have shown in Figs. 5 and 6 modified devices for performing the same operation.

In Fig. 5 the pinions H on the shaft G are replaced by a bevel-gear H⁵, which meshes with a similar gear H⁶ on a shaft carrying a sprocket-wheel H⁷. A sprocket-chain H⁸ passes around the sprocket H⁷ and a similar sprocket H⁹ on the trunnion of the first case D. A second sprocket H¹⁰ on the same trunnion drives a sprocket-chain H¹¹, which passes over similar sprockets on the trunnions of the succeeding cases D, around the sprocket H¹² on the last case, returning to the first sprocket H¹⁰. The alternating rotary movement of the shaft G will, through the gearing described, cause the cases D to rotate and move on their trunnions or on a suitably-prepared floor to and fro in the manner heretofore described, except the first and last cases, which will be mounted in stationary boxes, so as to have simply a rotary motion and not a linear motion. While I have shown the sprocket-wheel H⁹ as fixed on the trunnion of the first case D, it is to be understood that it may be placed on an independent shaft, with a sprocket-wheel similar to H¹⁰ on the same shaft, around which the chain H¹¹ will pass, a sprocket similar to H¹² in such event being placed on an independent shaft beyond the last case and having the chain H¹¹ passing around the same. By this arrangement all the cases will partake of the linear as well as the rolling motion.

Fig. 6 shows a longitudinal shaft H¹³, driven by bevel-gears H⁵ and H⁶ from the shaft G, on which are placed a series of screws H¹⁴, adapted to engage with and turn worm-gears H¹⁵ on the trunnions of the cases D, moving them in the same way as heretofore described.

From the above it will be readily understood that the same means used for rolling the cases also keeps them separated from one another a predetermined distance and that the speed-regulating mechanism is so constructed and arranged that it will operate successfully even when the power applied

thereto is much greater than that heretofore used for operating a pendulum mechanism.

I have illustrated and described the preferred construction and arrangement of parts entering into my invention; but it is obvious that changes can be made therein without departing from the essential features of my invention.

Having thus described my invention, I claim—

1. An apparatus for preserving perishable articles, consisting of rotatable packing-cases adapted to inclose the perishable articles, means for imparting a rotary and linear movement to the cases, and means for regulating the speed of the rotary and linear movement of the cases, substantially as described.

2. An apparatus for preserving perishable articles, consisting of rotatable packing-cases having trunnions, supports upon and over which said trunnions may travel, means for imparting a rotary and linear movement to the cases, and means for regulating the speed of said rotary and linear movement, substantially as described.

3. A support for cases, cases having trunnions by means of which they are supported thereon, notched bars adapted to engage with the trunnions and roll the cases, means for imparting a backward-and-forward movement to the notched bars, and means for regulating the speed of rotation of the cases, substantially as set forth.

4. A support for cases, cases having trunnions by means of which they are supported thereon, notched bars adapted to engage with the trunnions and roll the cases, a mutilated-gear mechanism for giving the notched bars a to-and-fro movement, means for operating the mutilated gearing, and a speed-regulating device, substantially as set forth.

5. A support for cases, cases supported thereon by means of trunnions, notched bars in engagement with the trunnions, a mutilated-gear mechanism adapted to reciprocate the notched bars, a cord and weight adapted to operate the mutilated gearing, and a pendulum-regulating device also operated by the cord and weight, substantially as set forth.

6. An apparatus for preserving perishable articles, consisting of rotatable packing-cases, and means for imparting a rotary and linear movement to said cases and holding them a predetermined distance apart, substantially as described.

7. An apparatus for preserving perishable articles, consisting of rotatable packing-cases, and means for imparting a rotary and linear back-and-forth movement to said cases and holding them a predetermined distance apart, substantially as described.

8. An apparatus for preserving perishable articles, consisting of rotatable packing-cases, means for rolling said cases in a linear direction and keeping them spaced apart, and means for regulating the speed of the rolling means, substantially as described.

9. In an apparatus for preventing the deterioration of perishable substances, in combination with holding-cases, and mechanism for operating said cases, of a shaft, gearing 5 on the shaft for driving said mechanism, a bevel-gear on said shaft, a shaft I, two mutilated bevel-gears oppositely fixed on said shaft I and adapted to alternately drive the aforesaid bevel-gear and automatically change the

direction of rotation of the holding-cases, ¹⁰ and means for driving the shaft I, substantially as set forth.

In testimony whereof I affix my signature in presence of two witnesses.

WILLIAM ALBERT SHELDON.
